UNITED STATES PATENT OFFICE

GERTRUDE C. WATSON, OF HOUSTON, TEXAS

IRON

Application filed October 18, 1928. Serial No. 400,535.

This invention relates to new and useful improvements in an iron.

One object of the invention is to provide a novel type of iron for smoothing cloth and adapted to be attached to and operated by a sewing machine.

Another object of the invention is to provide a device of the character described, which includes cooperating smoothing rollers one of which is equipped with heating means, said device including means for driving one of said rollers from the momentum wheel of said machine.

With the above and other objects in view, the invention has particular relation to certain novel features of construction, operation and arrangement of parts, an example of which is given in this specification illustrated in the accompanying drawings herein.

Figure 1 shows a side view of a sewing machine with the device attached thereto and

Figure 2 shows an end view thereof, showing the device partly in section.

In the drawings the numeral 1 designates a sewing machine as a whole and the numeral 2 designates the arm thereof. This sewing machine may be of any conventional construction having the momentum wheel 3 which may be clutched with and declutched from the operating mechanism of the machine in the usual manner. Fastened to the arm 2 there is a clamp 4 having the side arms 5, 5 provided with aligned bearings 6, 6 spaced apart. There is a smoothing roller 7 whose shaft 8 rotates in said bearings. One end of the shaft 8 has a driving wheel 9 thereon adapted to be clutched therewith and declutched therefrom in any conventional manner and this wheel 9 has a peripheral groove in which the momentum wheel 3 runs. The driving wheel 9 is driven by friction from the momentum wheel 3.

Suitably secured to the bearings 6 are the flexible arms 10, 10, whose free ends have the bearings 11, 11 which are aligned and in which shaft 12 rotates. Mounted on the shaft 12 is the smoothing roller 13. The arms 10 are substantially U shaped and the roller 13 confronts and is yieldably held against the

roller 7 by said arm. If desired an electrical heating element may be located with the roller 13 and this element may be connected with a source of electrical energy through the wiring 14 in any approved manner. When it is desired to use the device the momentum wheel 3 may be declutched from the operating mechanism of the machine and the roller 7 may then be operated from said momentum wheel without operating the machine itself. The cloth may be passed between said rollers in an obvious manner.

When the sewing machine is to be used, the clutch of the momentum wheel 3 may be engaged and the clutch of driving wheel 9 disengaged so that the ironing device will not be operated.

The drawings and description disclose a preferred form of the invention by way of illustration only while the broad principle of the invention will be defined by the appended claims.

What I claim is:

1. A device of the character described including a support, a momentum wheel thereon, a bracket on the support having two pairs of spaced bearings, flexible, U-shaped arms supporting one of said pair of bearings, confronting rollers mounted in said respective pairs of bearings, one of said rollers having an extended shaft, a drive wheel on said shaft in operative contact with said momentum wheel, and a heating element in one of said rollers.

2. A device of the character described including a support, a bracket thereon having spaced bearings, a smoothing roller mounted in said bearings, flexible, U-shaped arms carried by the bracket and having aligned bearings, roller mounted in the arm bearings and confronting said smoothing roller, a driving wheel carried by one of said rollers, a momentum wheel on said support and in driving connection with said driving wheel, and a heating element in one of said rollers.

3. An attachment for sewing machines including a bracket adapted to be attached to the machine, a driving roller mounted on said bracket to rotate on a fixed axis, a driven roller arranged to cooperate with said driv-

ing roller, means for mounting the driven roller in such co-operating relation with the driving roller, said mounting means comprising flexible supporting arms shaped to provide an entrant space at the ends of the rollers whereby material to be pressed may be passed between the rollers in a direction longitudinally of said rollers.

4. An attachment for sewing machines including a roller supporting device attached to the machine, a driving roller mounted in fixed bearings on said supporting device, a roller mounted in movable bearings and arranged to cooperate with said fixed rollers, means for mounting the movable bearings, said means comprising arms, substantially U-shaped to permit the material between said rollers to be moved in a direction lengthwise of the rollers and to pass beyond the ends of the rollers.

In testimony whereof I have signed my name to this specification.

GERTRUDE C. WATSON.
